UNITED STATES PATENT OFFICE

155,916

DESIGN FOR A SALAD DISH OR SIMILAR ARTICLE

Annie H. Masche, Charleston, S. C.

Application April 23, 1948, Serial No. 145,927

Term of patent 7 years

(Cl. D44—15)

To all whom it may concern:

Be it known that I, Annie H. Masche, a citizen of the United States, residing at Charleston, in the county of Charleston and State of South Carolina, have invented a new, original, and ornamental Design for a Salad Dish or Similar Article, of which the following is a specification, reference being had to the accompanying drawings, forming a part thereof.

I claim:

The ornamental design for a salad dish or similar article, as shown.

ANNIE H. MASCHE.
